UNITED STATES PATENT OFFICE

CHARLES J. MATSCH, OF LAKE CITY, MINNESOTA

AIR HEATING AND HUMIDIFYING APPARATUS

Application filed May 18, 1931. Serial No. 538,276.

The present invention relates to an apparatus designed for use with a furnace or the like and has for its prime object to provide means for heating and humidifying air.

Another very important object of the invention resides in the provision of an apparatus of this character which utilizes the heat from the gaseous products of combustion.

A still further very important object of the invention resides in the provision of an air heating and humidifying apparatus which is exceedingly simple in construction, inexpensive to manufacture, thoroughly efficient and reliable in use and operation, durable, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of the apparatus embodying the features of my invention.

Figure 2 is a vertical section therethrough, and

Figure 3 is a top plan view of the water pan.

Referring to the drawings in detail it will be seen that the numeral 5 denotes a hot air furnace or the like from which extends a pipe 6 for taking off the products of combustion. Pipe 7 represents the means used for taking off the heated air. The parts thus far described are not of the essence of my invention but have been illustrated merely to exemplify clearly one use of the improved apparatus.

This apparatus utilizes a cylindrical casting comprising a lower section 8, and upper section 9 and a cap 10. Numeral 11 denotes a cylindrical water pan having an annular groove in its bottom to receive the upper edge of the section 8 and an annular groove in its upper edge to receive the bottom edge of the section 9. A collar 12 rises from an opening

in the bottom of the pan and a pipe 14 extends through this collar terminating a slight distance above the pan and leads to a source of fresh air such as to the exterior of the building in which the apparatus is installed. The bottom edge of the section 8 rests in an annular groove in the base ring 15.

Pipe 6 is attached to or merged into a pipe 6' which extends through the section 9 and is then offset downwardly as at 16 and merges into a lower horizontal section 26 which extends through an opening in the section 9 and over the end of the lower section 26 there is disposed a suitable closure 17. Pipe 27 rises from the lower section 26 through the top 10 merging into an elbow 28 from which extends a pipe 29 to the chimney structure 30. A pipe 31 rises from an opening in the top 10 to a register 32. A pipe 33 rises from an opening in the top 10 to a register 34 to which the pipe 7 also extends. This arrangement of utilizing the hot air, of course, is not of the essence of the invention but has been illustrated as a practical exemplification.

It will be readily apparent that the products of combustion from the furnace must pass through the pipes 6, 6' and through the pipe 27 and of course will heat the air in the drum and this air will be moistened by the water in the pan 11 and the air in the drum will be supplied through the pipe 14 and will rise through pipes 31 and 33 or the like.

A very important feature of this invention is in the manner of supplying water to the pan 11, and in this connection, it will be seen that the water from any suitable source of supply is fed through a pipe 35 equipped exteriorly of the drum with a suitable valve, and at its outlet end extending through the wall of the section 9. On its inner end, the pipe 35 is provided with a spray nozzle 36 so that, as is apparent the water is supplied to the pan 11 in the form of a fine spray or mist, thus furnishing immediately the humidity to the air passing through the drum. Such means permits comparative simplicity in construction and easy regulation or control of the device.

The pan 11 is provided with a vertical overflow pipe 37 from the bottom of which and through the section 8 leads a drain pipe 38.

It is thought that the construction, utility, operation and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

25. 1. An apparatus of the class described including a drum formed in two sections, a water pan interposed between the sections, a conduit for products of combustion passing through the drum above the pan, cold air intake means associated with the drum at the bottom thereof and hot air take off means associated with the top of the drum, said conduit comprising a pipe extending through one side of the drum and being offset downwardly intermediate its ends to extend through the opposite side of the drum and having a closure at last mentioned opening and a pipe rising from the lower portion of the conduit through the top of the drum.
30. 2. In combination with a stack and a furnace, a drum separable from and arranged between the furnace and stack, a pipe extending through the drum and connecting the stack and furnace and consisting of a plurality of angularly arranged sections forming a tortuous passage for the products of combustion, an open top water pan arranged in the drum in proximity to one of said pipe sections, a cold air pipe extending into the drum and having an upwardly directed inner end extending through and terminating above the bottom of said water pan, a water pipe leading into said drum above the water pan, means on the inner end of said water pipe for producing a spray of water, and a pipe extending upwardly from the drum for conveying hot air to a hot air register.
35. 3. In combination with a furnace and a stack, a drum, a water pan in the drum, a pipe extending through the drum and connecting the furnace and stack, said pipe having a part thereof in close proximity to the water pan, pipes extending from the drum for conveying hot air to hot air registers; a cold air conduit entering the drum adjacent

the bottom thereof and having its inner end extending through the pan and terminating above the water level, a water pipe leading into said drum, and means on the inner end of said water pipe for producing a spray of water above said pan.

In testimony whereof I affix my signature.
CHARLES J. MATSCH.
